UNITED STATES PATENT OFFICE.

GIOVANNI RIVETTA, OF PARIS, FRANCE.

CENTRIFUGAL FORCE GOVERNOR.

Application filed July 12, 1921. Serial No. 484,271.

To all whom it may concern:

Be it known that I, GIOVANNI RIVETTA, engineer, subject of the King of Italy, residing at Paris, France, have invented certain new and useful Improvements in Centrifugal Force Governors, of which the following is a specification.

This invention relates to improvements in centrifugal governors.

10 The centrifugal governing device according to the present invention comprises essentially in combination, a spindle, a rotary mass pivoted centrally on said spindle, a spring tending to maintain the pivoted mass in an oblique position relatively to said spindle, and a stationary brake ring concentrically encircling the rotary spindle, against the inner surface of which ring the mass tends to engage when rotated.

20 In order that the invention may be clearly understood it will be described, by way of example, with reference to the accompanying drawing in which:

Figure 1 is a sectional view, and

25 Figure 2 is an underside view.

The governor comprises a mass M, obliquely arranged relatively to a spindle A by which said mass is driven. The spindle A passes through the center of the mass M to which it is pivotally connected by a pin a. The mass M is held in an oblique position by means of a spring R.

It will be seen that as soon as a rotary motion is imparted to the spindle A, the mass M owing to the centrifugal force tends to assume a position perpendicular to the spindle A.

The mass M being surrounded by a stationary tube T, as shown, it follows that when the mass M tends to assume a perpendicular position and engages the tube, a braking action will be exerted by the tube T.

The mass M tends to resume its former position under the action of the spring R.

As may be seen from the drawings, the mass M may be prevented from coming into frictional contact with the inner wall of the tube by the small blocks XY of a suitable hardness, which blocks may be changed when worn out.

The speed of the apparatus is regulated by varying the tension of the spring R and therefore modifying the braking force of the mass M.

What I claim is:

1. A centrifugal governor comprising in combination a rotary spindle, a rotary mass pivoted centrally on said spindle, a spring tending to maintain the pivoted mass in an oblique position relatively to the spindle and a stationary brake ring concentrically surrounding the rotary spindle against the inner surface of which the mass tends to engage when rotated.

2. A centrifugal governor comprising in combination a rotary spindle, a rotary mass pivoted centrally on said spindle, hardened blocks carried by the said mass, a spring tending to maintain the pivoted mass in an oblique position relatively to the spindle, and a stationary brake ring against the inner surface of which the blocks tend to engage when the spindle is rotated.

ING. GIOVANNI RIVETTA.
